UNITED STATES PATENT OFFICE.

JOHN W. FOREST, OF THAYER, AND SAMUEL H. SCOTT, OF CHANUTE, KANSAS.

CAR-COUPING.

SPECIFICATION forming part of Letters Patent No. 396,201, dated January 15, 1889.

Application filed September 21, 1888. Serial No. 286,044. (No model.)

To all whom it may concern:

Be it known that we, JOHN W. FOREST, of Thayer, Neosho county, Kansas, and SAMUEL H. SCOTT, both citizens of the United States, 5 the latter residing at Chanute, in the county of Neosho and State of Kansas, have invented a new and useful Improvement in Car-Couplings, of which the following is a specification.

The invention relates to improvements in 10 car-couplers; and it consists in the construction and novel combination of parts, herein-after described, illustrated in the drawings, and pointed out in the claims hereto appended.

In the drawings, Figure 1 is a perspective view of the end of a car with a draw-head embodying the invention attached. Fig. 2 is a central horizontal section of two of such draw-heads coupled together, with the chains secured at their inner ends to the locking-blocks. Fig. 3 is a perspective view of one of the locking-blocks detached. Fig. 4 is a detail view of the face of the projection of one of the draw-heads to show the seat therein of one of the locking-blocks.

25 Referring to the drawings by letter, A designates a draw-head suitably secured to the adjacent end of a car and provided with the recess B, into which the projection a of the opposite draw-head enters, which projection 30 is rounded at its end, as shown. The said recess is provided with the roof or web b, and with the outwardly-curved directing arm or plate b' to guide the rounded end of the projection a of the opposite draw-head into the recess B, 35 the roof or web b of which rides over this projection a. The said projection is provided with the transverse horizontal opening C, having the outer rectangular portion, c, and the inner portion, c', T-shaped in cross-section.

40 D is a recess in the inner surface of the projection a, having its front and rear sides, d d', respectively inclined and converging inward on each side of the opening C, which forms a seat for the corresponding locking-block, E.

45 The said locking-block has the rectangular shank e seated in the opening C, and is provided on its inner side and end with the opposite flanges or studs e' e', seated in the upper and lower extensions of the inner T-shaped 50 portions, c', of said opening. The inner end

of the locking-block is beveled outwardly at e², and it has on its inner side a shoulder, e³, formed by notching said edge, which shoulder can catch over the side of the outer orifice of the opening C, when the locking-block 55 is drawn outward and prevents the latter from being moved inward into coupling position. The end of the projection a is provided with a transverse recess and upper and lower coupling-pin holes to couple with the common link 60 and pin.

F is a strong spring-bar having one end secured to the outer side of the projection a and the other end passed through a loop or staple, f, on the outer end of the corresponding locking-block, and G is a chain having the coiled spring g secured between its outer and inner sections. The inner end of said chain is secured to the staple f and its outer end to a crank-arm at the lower end, h, of the rod H, 70 journaled in bearings secured at proper points to the end of the car and provided thereabove with the actuating handle or wheel h'. The said coiled spring makes the chain elastic, and thereby prevents breakage when the chain is 75 under tension.

The action of the coupler is as follows: When the draw-heads come together, the beveled ends of the locking-blocks will ride over each other in the recess D and their rear surfaces 80 will catch against each other, the locking-blocks being forced inward by the springs F. The said blocks are unlocked by pulling on the chains G, either at the sides of the car or from the top by means of the rod H and the wheel 85 or handle and crank-arm thereon.

The blocks may be retained unlocked by turning the crank-arm h past its center or by engaging the shoulder e³ on the side of the outer orifice of the opening C. The flanges 90 on the locking-block steady the latter and give it a wider bearing-surface on the opposite block.

Having described our invention, we claim—

1. The combination of the draw-heads, each 95 having a recess, B, and a projection, a, the projection a being provided with a transverse opening having a rectangular portion, c, and a T-shaped portion, c', and the locking-block having a rectangular portion fitting in the 100

portion *c* of the opening, and the flanges *e'*, fitting in the T-shaped portion thereof, as specified.

2. In a car-coupler, the combination, with the draw-head provided with the recess *B*, the opening *C*, and recess *D*, of the locking-block *E*, provided with the flanges *e'*, beveled point *e²*, and shoulder *e³* on its inner edge, the spring-rod *F*, and the chain *G*, substantially as specified.

In testimony that we claim the foregoing as

our own we have hereto affixed our signatures in presence of two witnesses.

JOHN W. FOREST.
SAMUEL H. SCOTT.
